UNITED STATES PATENT OFFICE

2,406,109

RINSE WRINGER

Albert Schellenberg, Joliet, Ill.

Application May 15, 1941, Serial No. 393,522

6 Claims. (Cl. 68—22)

1

This invention relates to wringers of the type used in connection with motor driven domestic washing machines, and particularly to that type of wringer wherein a rinsing operation is performed. This application is an improvement on my co-pending application, No. 368,159, filed December 2, 1940, now Patent No. 2,358,256, granted Sept. 12, 1944.

The particular object of the present invention is to provide improved conveyor and rinsing means in the rinse chamber of the wringer.

Other objects and benefits will be disclosed in the following descriptions and drawing, in which the figure is a cross-sectional elevation view of a rinse wringer having a conveyor belt over the lower rolls and a large intermediate roller co-acting with the belt to agitate and rinse garments passing between the two sets of rolls.

It will be understood that the wringer, shown somewhat diagrammatically in the foregoing drawing, employs the reversible gear head driving the rolls and conveyor mechanism, the safety pressure release for the upper frame, the clutch to stop operations of the rolls and conveyor when pressure is released, the rinse basin overflow, and generally all necessary mechanical structure shown in my prior application, Serial No. 368,159, filed December 2, 1940, now Patent No. 2,358,256, granted Sept. 12, 1944, together with any necessary modifications of this structure as could be accomplished by skillful mechanics experienced in the art. It will be appreciated that the present application deals with detailed modifications of structure with the basic mechanism of the wringer remaining practically the same as shown in the aforesaid application.

Now referring to the drawing, I designate the lower frames by the numeral 10 and the upper frames by the numeral 11. The dual pairs of driving rolls in Fig. 1 are designated 14—15 and 16—17. The water level in the rinse chamber in each case is designated by the letter L.

Now referring to Fig. 1, the belt 18 over the lower rollers 14, 16 co-acts with a large intermediate roller 20 resiliently mounted on bearings 22 by compression springs 23. It will be appreciated that by this mounting the roller 20 is permitted to move upward when thick portions of clothing pass thru the rinse chamber. The roller 20 may be either plain or corrugated as shown at 20'. Mounted interiorly of the roller 20 are baffles 21 which pick up water from the rinse basin, as well as that sprayed by the spray tube S1 and deliver it through the perforations 21' as will be readily understood.

2

I also provide an automatic release when unusually thick garments are fed in the wringer. By referring to the description of the release mechanism R in the application Serial No. 368,159, it will be appreciated that when the roll 20 is raised to the point where it strikes the release mechanism R at P, the top frame will be released and the drive to the rolls 14—15, 16—17, and 20 will be stopped.

The intake rolls 14 and 15 are adapted to receive the clothes therebetween which are then transmitted over the belt 18 beneath the roller 20, to the discharge rolls 16 and 17. The flexibility of the belt allows the clothes to be deflected by the corrugated periphery of the roller 20 so that the clothes are deflected laterally of their direction of movement during their passage through the rinse water, and thus are thoroughly saturated with the rinse water to obtain an effective rinsing operation.

Having thus described my invention, I claim:

1. In a rinse wringer having a rinsing chamber, means for conveying garments through said rinsing chamber including an impeller roll mounted in the rinsing chamber, said roll being hollow and cylindrical with a corrugated peripheral wall having perforations at intervals therein.

2. In a rinse wringer having a rinsing chamber, means for conveying garments through said rinsing chamber including an impeller roll mounted in the rinsing chamber, said roll being hollow and cylindrical with a corrugated peripheral wall having perforations at intervals therein, and radially extending baffles within said roll at the peripheral wall thereof.

3. In a rinse wringer having a rinsing chamber, means for conveying garments through said rinsing chamber including an impeller roll mounted in the rinsing chamber, said roll being hollow and cylindrical with a corrugated peripheral wall having perforations at intervals therein, radially extending baffles within said roll at the peripheral wall thereof, and means within said roll for applying a rinsing spray toward the peripheral wall thereof.

4. In a rinse wringer having a rinsing chamber, means for conveying garments through said rinsing chamber including an impeller roll mounted in the rinsing chamber, said roll being hollow and cylindrical with a corrugated peripheral wall having perforations at intervals therein, and means within said roll for applying a rinsing spray toward the peripheral wall thereof.

5. In a rinse wringer, a rinsing chamber, an upper frame mounted on the rinsing chamber, a

pair comprising upper and lower intake rolls at one side of the rinsing chamber, a pair comprising upper and lower discharge rolls at the opposite side of the rinsing chamber, a conveyor belt extending between the lower rolls of said pairs of rolls, and roller means mounted on the upper frame between the pairs of rolls coating with said belt to agitate and rinse garments, said roller means comprising a hollow impeller roll having peripheral corrugations, said corrugated periphery being perforated at intervals therearound.

6. In a rinse wringer, a lower frame, an upper frame releasably locked on the lower frame and

coating therewith to form a rinsing chamber, a pair of upper and lower intake rolls at one end of the rinsing chamber, a pair of upper and lower discharge rolls at the opposite end of the rinsing chamber, a conveyor belt extending over the lower rolls of said pairs of rolls and being driven thereby, and roller means mounted on the upper frame between the pairs of rolls coating with said belt to agitate and rinse garments, said roller means comprising a hollow impeller roll having peripheral corrugations, said corrugated periphery being perforated at intervals therearound.

ALBERT SCHELLENBERG.
